UNITED STATES PATENT OFFICE.

JOHN C. RINGE, OF BRIDGEPORT, CONNECTICUT, ASSIGNOR TO THE SINGER MANUFACTURING COMPANY, A CORPORATION OF NEW JERSEY.

SEAM FOR SEWED ARTICLES.

1,181,169.

Specification of Letters Patent.

Patented May 2, 1916.

Application filed September 15, 1911. Serial No. 649,568.

To all whom it may concern:

Be it known that I, JOHN C. RINGE, a citizen of the United States, residing at Bridgeport, in the county of Fairfield and State of Connecticut, have invented certain new and useful Improvements in Seams for Sewed Articles, of which the following is a specification, reference being had therein to the accompanying drawings.

This invention relates to an improvement in seams for sewed articles and particularly to an arrangement of threads and fabrics for uniting and confining the raw edges of two pieces of heavy fabrics, such as carpets, rugs, mattings, etc., the object being to provide a seam which shall be very strong and elastic and which will effectually protect the raw edges, and present no objectionable ridge if opened or spread out flat.

In the accompanying drawing, the single figure is a top plan view of the improved seam. In forming the improved double chain-stitch overedge seam, the needle is first passed through the fabric carrying the thread *b* in the formation of the through-and-through stitches, when the needle is returned slightly and forms the loop *a* followed by the looper carrying the thread *d* through the loop *a* in the formation of the loop *e*, which latter is held open by a suitable spreader to receive the needle, which in the meantime has been returned to its

initial position, in the formation of the next subsequent stitch, the looper meanwhile retreating from the loop *a* when it reverses its movement and crosses the edge of the fabric and forms the loop *c* in the path of the needle as it is again moved to pierce the fabric, and as soon as the needle has entered the fabric the looper retreats and recrosses the edge of the fabric, which effects the cross stitch and while performing this last function it is again moved forward into the next subsequently formed loop *a*.

Claim:—

A multiple thread overedge seam comprising, in combination with the fabric, a thread *b* extending along the face of the fabric and having a series of loops *a* passed through the same and another thread *d* passing, in loop form, through the loops *a* at the opposite face of the fabric, the thread *d* in its lead from one to the next subsequent stitch being crossed upon itself as it is passed from one to the opposite side of the fabric forming the loops *c* encircling the loops *a* upon the first named face of the fabric.

In testimony whereof, I have signed my name to this specification, in the presence of two subscribing witnesses.

JOHN C. RINGE.
